RATCHET MEASURING WRENCH

Filed Sept. 10, 1942

UNITED STATES PATENT OFFICE

2,374,217

RATCHET MEASURING WRENCH

Kenneth R. Larson, Des Plaines, Ill., and George M. Walraven, Kenosha, Wis., assignors to Snap-On Tools Corporation, Kenosha, Wis.

Application September 10, 1942, Serial No. 457,866

7 Claims. (Cl. 73—139)

This invention relates to turning devices and more particularly to nut turning torque ratchet wrenches, although certain features thereof may be employed with equal advantage for other purposes.

It contemplates more especially the adaptation of a self-contained ratchet mechanism to a simple, dependable, accurate and compact torque wrench of the type described in the copending Larson patent application, Serial Number 374,361, and filed January 14, 1941, which eventuated into Patent No. 2,312,104, dated February 23, 1943.

Numerous types of torque turning wrenches have been in widespread use, but these are of the flexible torque resisting beam type wherein ratchet mechanisms can more easily be supplied than in torsion type load measuring devices such as illustrated in the aforesaid copending application for Letters Patent. There has been a long felt want for ratchet torque turning tools, and these should be compact, dependable, and accurate as well as light in weight and effective in operation. This coupled with the fact that the turning head constitutes the torsion resisting element which should be as long and unaffected as possible by any other influences, complicates the adaptation of ratchet mechanisms thereto. A torque wrench of the specified type that presents a ratchet problem is fully described in the above referred to copending application and Letters Patent.

One object of the present invention is to simplify the construction and improve the operation of devices of the character mentioned.

Another object is to incorporate compact, dependable, and durable ratcheting expedients into a nut turning or other type of a torque wrench head member presenting limited space and special operating instrumentalities.

Still another object is to provide an improved torsion shank and ratchet member embodying a double toothed pawl that is circumferentially spaced to provide registry with an annular ratchet member comprising part of a sectional turning head.

A further object is to provide a measuring wrench shank with a plurality of circumferentially spaced pawl teeth that are operatively connected to an actuator to place one or the other of the pawl teeth in and out of registry therewith for operative head turning engagement in selected directions of rotation.

A still further object is to provide a plurality of pawl teeth in a casing attached to a measuring shank concentric to the axis of rotation

thereof to comprise a reversible ratchet head with a turning member.

Still a further object is to provide a plurality of pawl teeth operatively connected with an axially positioned actuator for controlled directional engagement with at ratchet head comprising part of a torsion resisting turning member.

An additional object is to provide a plurality of pawl teeth in a head member for selected registry with circumferentially spaced pawl engaging members on a revoluble turning member for engagement by one or the other of the opposite pawls to constitute a torque indicator actuator element.

Other objects and advantages will appear from the following description of an illustrative embodiment of the present invention.

In the drawing:

Figure 1 is a fragmentary, partly sectional side view in elevation of a measuring wrench having a ratchet mechanism associated therewith in accordance with the teachings of the present invention.

Figure 2 is a fragmentary bottom plan view of the wrench cover plate shown in Figure 1 with the enclosing casing removed therefrom.

Figure 3 is a fragmentary sectional view in elevation taken substantially along line III—III of Figure 2.

Figure 4 is a fragmentary sectional view taken substantially along line IV—IV of Figure 3.

Figure 5 is a perspective view of the ratchet member embodying an element of the structure shown in Figures 1 to 4 inclusive.

Figure 6 is a perspective view of the double-toothed pawl constituting a complement of the ratchet member shown in Figure 5.

Figure 7 is a perspective view of the pawl actuator shown in assembled relation with the other instrumentalities in Figures 1 and 3.

The structure selected for illustration comprises a solid handle member 10 of standard construction having an elongated chambered wrench shank or body 11 cast or otherwise shaped to present side walls 12 and 13 terminating in a semicircular top or head extremity 14. The handle 10 with its chambered body 11 is preferably though not essentially cast from an aluminum alloy so as to possess the desired strength and lightness for convenience and manipulation in nut turning as will appear more fully hereinafter.

It will be observed that the handle shank or body 11 consists of the side walls 12—13 which are preferably though not essentially inclined and converge in the direction of the handle 10 and

also toward the bottom wall 15 formed integral therewith to define an elongated chambered interior 16.

It should be noted that, in this instance, the side walls 12-13 not only converge toward the handle 10 but also toward the bottom 15 to define a compact and well balanced casing or body 11 more fully disclosed and described in our co-pending application serially numbered 417,126 and filed October 30, 1941. The body or casing shank 11 is, in this instance, covered by a rigid steel plate 17 that is shaped to conform with the configuration of the peripherally flanged open side 18 opposite the bottom wall 15 to confront therewith and serve as a complement thereof. The lower or handle extremity 19 of the chamber 16 is of the same general size and semi-circular configuration as the head extremity 14.

The peripherally flanged open edge 18 of the casing 11 extends around the side walls 12-13 and their semi-circular head and handle extremities 14 and 19. The rigid face or cover plate 17 is shaped to correspond with the flanged open edge 18 including its upper and lower semi-circular head and handle extremities 14 and 19 to serve as an enclosure therefor and also as a rigid turning arm to which the measuring instrumentalities are attached as will appear more fully hereinafter. A plurality of threaded screw fasteners 20 project through apertures 21 in the rigid cover plate 17 to engage correspondingly threaded bores 22 in the peripheral casing edge 18 that extends along the side walls 12-13 of the handle shank or casing body 11 and semi-circular ends 14-19, thereby enclosing the chamber 16 and confining the torsion displacing, indicating, and measuring instrumentalities to be described hereinafter.

It should be noted that the handle shank or casing body 11 and the side walls 12-13 are provided with a sufficient number of apertures 21 and threaded bores 22 uniformly spaced along the entire peripheral flange 18 so that the comparatively rigid and load carrying cover plate 17 can be effectively attached to the casing body 11 which is greatly strengthened and reinforced therewith. In fact, the casing 11 does not sustain any appreciable turning load and primarily serves to confine the measuring instrumentalities as a protection against foreign substances and impacts. The cover plate 17 is sufficiently rigid to avoid a flex, distortion or consequential variation under turning load.

The semi-circular head 14 of the body 11 is provided with a circular recess 23 corresponding substantially in curvature therewith and sized to freely receive a housing or body member 24 of substantially smaller size for free rotation therein. The housing or body member 24 is formed, in this instance, integral with a substantially smaller cylindrical shank 25 that terminates in a somewhat enlarged polygonal shoulder 26 (Figure 3). The polygonal shoulder 26 is formed integral with the shank 25 in axial relation to the housing or body member 24.

The polygonal shoulder 26 registers with a correspondingly sized and shaped opening 27 provided in the cover plate 17 coaxially with a circular aperture 28 (Figure 3) provided in the confronting bottom wall 15 of the casing 11. As shown, the housing or body member 24 is confined within the head 14 of the casing 11 and is disposed adjacent the bottom 15 for free rotation therein except for the fixed association be-

tween the polygonal shoulder 26 and the cover plate 17. To this end, the polygonal shoulder 26 of the shank 25, is flush with the cover plate 17 and is preferably though not essentially welded thereto for fixed connection therewith. For that matter, the somewhat enlarged shoulder 26 of the turning shank 25 and the housing or body member 24, may contact the inner surface of the cover plate 17 and be welded thereto around the peripheral edge thereof either from the exterior or interior or both surfaces of the cover plate 17 depending upon the dictates of commercial practice.

The housing or body member 24 has, in this instance, a circular recess 29 provided axially therein through the bottom end surface 30 thereof. The housing or body member 24 cooperates with an axially disposed work engaging member 32 telescoped in the axial recess 29 thereof for radial confronting relation therewith for connection through a ratcheting mechanism to be hereinafter described. A polygonal wrench socket receiving shank 33 is, in this instance, formed integral with the work engaging member 32 which freely projects through the bore or aperture 28 provided in the bottom wall of the head 14. The work engaging wrench socket receiving shank 33 projects beyond the bottom 15 of the casing shank 11 to provide accessibility to fasteners such as nuts for turning to a predetermined degree.

A spring impelled detent 35 of standard construction is provided in a face of the polygonal shank 33 for cooperation with a correspondingly sized and shaped recess provided in a wrench socket or other turning implement that is telescoped thereon for retention thereon against accidental detachment. Wrench sockets or other turning implements (not shown) would normally be provided with a recessed shank shaped and sized to conform with the polygonal shank 33 of the revoluble work engaging member 32 so that the friction exerted by the spring impelled detent 35 would be effective in retaining the turning implement thereon against accidental removal.

It should be noted that the housing or body member 24 is rigidly attached to the cover plate 17 that is preferably of rigid and non-yielding material such as steel, while the body or casing shank 11 may be cast or otherwise shaped from aluminum, in that the housing or body member 24 is mounted for movement relative thereto in sustaining the turning load. The casing 11 does not directly carry any appreciable load. Turning movement is imparted to a fastener such as a threaded nut through a wrench socket attached to the polygonal shank 33 of the revoluble work engaging member 32, responsive to manually applying force or effort to the handle 18 in one direction or another.

The revoluble member 32 has an annular shoulder 36 which is intermediate the cylindrical ends 37-38 journaled for support in an end bore 39 in the housing 24 and communicating with its internal chamber or recess 29. The other turning member shoulder 38 is journaled in a circular aperture 40 provided in a closure bearing plate 41 that is shaped to correspond with the substantially figure 8 contour of the head chamber or recess 29 that communicates with a pawl chamber or recess 42 provided in the housing or body member 24. Threaded fasteners 43 retain the closure plate 41 on a correspondingly shaped peripheral shoulder 44 that

defines the outline of the head and pawl chambers 29—42.

To enable ratcheting of the handle 10 with the housing or body member 24 in opposed directions to impart intermittent rotation responsive to oscillatory movement of the handle 10, the periphery of the revolute turning member shoulder 36 is provided with radially extending ratchet teeth 45 cut or otherwise formed for extension therefrom. As shown, the circular pawl recess 42 is provided in the housing or body member 24 to communicate with the chamber 29, it being in longitudinal alignment therewith to receive a correspondingly shaped circular pawl 46 journaled for rotation therein with the periphery thereof partially disposed in the chamber 29.

To this end, the pawl 46 has integral axial aligned hubs 47 and 48 received in correspondingly shaped bores 49 and 50 provided in the housing or body member 24 and closure plate 41. A circular knob 51 having a stem 52 with a polygonal end 53 is disposed for reception in a somewhat larger and correspondingly shaped polygonal recess 54 provided axially within the pawl hub 47 to establish fixed connection therewith to constitute a manual rotary adjustment for the pawl 46. A cotter pin 55 extends through an aperture 56 in the knob stem 52 in the inside of the body cover plate 17 (Figure 3) to retain the stem end 53 in registry with the pawl recess 54.

To enable ratcheting of the revolute work engaging member 32 in opposed directions by rotary adjustment of the knob 51 to extreme positions that may be designated on the body closure plate 17, the pawl 46 has the periphery thereof interrupted to define confronting pawl teeth 57 and 58. The pawl teeth 57 and 58 are complementary to the ratchet teeth 45 for independent meshing engagement therewith depending upon the rotary position of the pawl 46 which is adjusted by the knob 51 to control the directional rotation of the revolute member or ratchet wheel 36. The pawl teeth 57 and 58 are sufficiently spaced so that one or the other will be in operative engagement with a ratchet tooth 45 to enable the desired rotary throw of the housing or body member 24 with the closure plate 17 for ratcheting purposes, without interference with the inactive pawl tooth. During the ratcheting action, the pawl 46 partially rotates about its axis until the next successive ratchet tooth 45 is engaged by the active pawl tooth 57 or 58 depending upon the direction of the ratcheting action.

It will be observed that the pawl 46 is nominally supported by the axial hubs 47 and 48 on both sides thereof with the plate 44 providing a bearing therefor to sustain a load thereon; however the principal turning load is borne by the circular body of the pawl 46 bearing on the wall of the circular recess 42. To maintain the pawl 46 stationary and in adjusted positions for the desired directional ratcheting, a positioning ball or detent 59 is resiliently mounted on a spring 60 confined in a passage 61 provided longitudinally in an elongated extension 62 in the housing member 24 and projecting toward the handle 10. The passage 61 is in radial communication with the pawl receiving recess 42. The spring 60 urges the positioning detent or ball 59 in the direction of the pawl 46 for engagement with the periphery thereof. To this end, the periphery of the pawl 46 is provided with conical

cavities 63 and 64 for reception of the resiliently mounted positioning ball or detent 59. The cavities 63 and 64 are spaced for selective registry with the detent 46 to hold the pawl teeth 57 and 58, respectively, in meshing engagement with the teeth 45 of the turning member 32, thereby enabling its rotation in a counterclockwise and clockwise direction (viewed from Figure 4) responsive to ratcheting or oscillating the handle 10.

It is thus apparent that the knob adjusting member 51 enables the ratchet member 32 to function in opposed directions with the dual pawl teeth 57—58 easily adjusted for the purpose set forth and without possible accidental displacement owing to the fact that the detent 59 is resiliently urged into the cavities 63 or 64 to retain the pawl 46 in its displaced position to control the direction of pawl tooth engagement. Consequently, when the wrench handle 10 with its casing 11 and cover plate 17 are turned to carry the nut turning load, the housing 24 and the revolute work engaging member 32 are operatively connected together to rotate as a unit 25 through the pawl 46.

However, when the handle 10, casing 11, and cover plate 17 are momentarily moved back to effect another bite or engagement between the ratchet teeth 45 and the pawl 46, the housing 24, casing 11, and cover plate 17 rotate relative to the then stationary work engaging member 32 to accomplish ratcheting action. In order to measure the extent to which any fastener such as a threaded nut is applied through the manipulation of the handle 10, the extent of twist sustained by the cylindrical extension 25 of the housing member 24 is determined in that this will be uniform for any predetermined applied force and will vary proportionately to the turning load imparted through the handle 10 that is primarily sustained by the rigid cover plate 17.

It will be observed that owing to the polygonal shoulder 26 on the shank 25 and the attachment thereof to the cover plate 17 in any suitable manner such as welding, any load turning movement applied to the handle 10 will be transferred to the cover plate 17 which, in turn, will rotarily displace the housing member 24 with its pawl connected work engaging member 32 which carries a nut or other turning implement. To the end that proportional twist is imparted to the cylindrical extension 25 anchored to the cover plate 17 at one extremity 26 and is free to twist at the other extremity 33 responsive to carrying the turning load, there is movement of the housing 24 proportional to the load on the revolute member 33. It is to be noted that the torsional stress will mostly be effective in the solid member 25 and to a negligible degree in the work engaging member 32.

In order to measure the degree of twist or torsion imparted to the revolute member 25 and work engaging member 32 responsive to any turning operation, an elongated cylindrical indicator displacing tube 65 is in this instance of uniform diameter, and projects radially through a passage 66 provided in the housing extension 62 for fixed press fitted engagement therein to constitute a single action unit or member therewith. The elongated rod 65 projects longitudinally of the body or casing shank 11 for confinement therein, although it is oppositely offset at both ends to align with the measuring instrument, as will appear more fully hereinafter.

So that the casing shank 11 together with its

associated instrumentalities may be as compact as possible, the cylindrical indicator displacing rod 65 is preferably disposed at a slight angle between the extremities 67 and 68 thereof (Figure 1) to avoid contact with either the bottom 15 or cover plate 17 and free to circumferentially move or oscillate for a limited extent depending upon the degree of twist imparted to the housing extension 62 or the torsion effect on the shank 25 responsive to carrying the turning load relative to its polygonal extremity 26 fixed to the cover plate 17.

The elongated indicator displacing tube or rod 65 need only be heavy enough to overcome the friction in the measuring instrumentalities and the load occasioned by their operation without causing any flex in the tube or rod 65. Its diametrical size, however, may be determined by other factors such as the elimination of backlash and conditions of abuse in actual nut turning operations. For that reason, the elongated tube or rod 65 in actual practice may be somewhat heavier than otherwise required merely to carry a comparatively negligible load of operating the measuring instrumentalities without any flex in the rod 65.

It may be more desirable from a manufacturing standpoint to terminate the elongated cylindrical rod 65 short of the lower circular handle casing formation 19 and cover plate circular extension 69 of the cover plate 17, with a reduced portion 70, and joined therewith to a rod extension 71 of comparatively smaller diameter. To this end, the rod extension 71 has its upper extremity projecting within an axial bore provided in the lower extremity of the reduced rod portion 70. The upper extremity of the rod extension 71 is frictionally engaged in the axial bore by means of a tapered tightening nut 72 that threadedly engages a correspondingly tapered and lower threaded extremity 73 of the reduced rod portion 70 to effect rigid connection of the rod extension 71 with the elongated cylindrical actuating rod 65 for the measuring instrumentalities.

With this arrangement, the rod extension 71 may be extended or retracted within the axial bore of the reduced rod portion 70 to enable longitudinal adjustment of the rod extension 71 relative to the indicator mechanism. The longitudinal adjustment of the rod extension 71 will vary the extent to which the dial mechanism is actuated or displaced responsive to a predetermined torsional stress imparted to the shank 25 of the interconnected housing and revolvable work engaging members 24-32. This enables also the replacement of the rod extension 71 should occasion demand or should such become impaired in any nut turning operation.

It should be noted that the rod 65 together with its reduced portion 70 and extension 71 function exactly the same even though these were turned or otherwise shaped to constitute an integral unit; however, such construction would be somewhat more expensive from a production standpoint than the co-axial connected rods 65-70-71 serving as an actuator for measuring instrumentalities when displaced by the twist imparted to the turning member shank 25. The reduced rod extension 71 has a right angularly offset extremity 74 which is confined within the casing body chamber 16 near the bottom end thereof, for registry with a longitudinally elongated slot provided in a lever 75 that comprises a part of the measuring and indicating instrumentalities 76-77 fully described in the Larson

copending application serially numbered 374,361 filed January 14, 1941, which eventuated into Letters Patent No. 2,312,104, dated February 23, 1943.

The measuring instrumentalities which are assembled as a unit on the dial casing plate that is attached to the exterior surface of the lower circular extremity 69 of the cover plate 17. Consequently, the measuring and indicator mechanism 76-77-71 can be attached to the cover plate 17 together with the housing 24, shank 25, revolvable turning member 32 and its torsion displacing rod 65-70-71. The cover plate 17 together with these instrumentalities are, in turn, attached for confinement in the chamber 16 of the body or casing shank 11 by means of fasteners such as the threaded studs 20.

It should be observed that the lower end of the chamber 16 of the body casing 11 is outwardly flared to define a circularly flared configuration 19 to conform with the size and shape of the lower extremity 69 of the cover plate 17 together with the dial casing plate and its confronting ring 77. It will be apparent from the foregoing arrangement of parts that a manual turning force applied to the handle 10 will impart a corresponding turning effect to the ratchet housing or body turning member 24. This creates a slight twist in the turning member extension or shank 25 which can be measured with the advantage procured through the moment arm dial indicator displacing member 65-70-71 therebetween.

This turning operation is transmitted to a suitable tool or implement or fastener such as a threaded nut, which requires a predetermined turning load in securing it to the desired degree of tightness for the suitable performance of its intended function. This turning movement and sustained turning load will create a fractional twist in the revolvable member shank or extension 25 primarily between its enlarged annular housing 24 and the polygonal stationary shoulder 26. This fractional twist created by the torsional effect on the cylindrical extension 25, will be translated to the measuring instrumentalities culminating in the rotary displacement of the pointer (not shown) responsive to its calibrated mechanism 76 through the medium of the elongated rod 65-70-71. The degree of twist or torsional strain within the turning member shank 25 is measured at the extreme end of the elongated rod 65-70-71, which is the point of its greatest displacement.

As a result, the rod 65-70-71 will accentuate the twist created in the revolvable head extension 25 to effectively turn the indicator pointer to an extent proportional to the length of the elongated rod 65-70-71. The measurement of the twist imparted to the revolvable head extension 25 at a point of maximum displacement of the comparatively long twist-translating rods 65-70-71 is an important factor in producing accurate readings. Then, too, the rod 65-70-71 need only be heavy enough to overcome the comparatively negligible force required to actuate the measuring instrumentalities, so that comparatively little friction is encountered between the housing 24, its revolvable turning member 32 and the measuring instrumentalities. This is conducive to accuracy accomplished with utmost simplicity in construction and operation.

With the arrangement of parts above described, the rod 65-70-71 comprising a single or sectional member is of such flexibility as to preclude injury to the dial mechanism in the event the handle 10 is abruptly released or the

turning load should fall by virtue of a rupture in the nut or bolt or other instrumentality that is being tightened. The rather flexible rod 65-70-71 and especially the part 71 would absorb a substantial part of the shock, without permitting such to damage the dial mechanism or any part thereof under abnormal conditions of abrupt release.

Any back-lash occasioned by the abrupt accidental release of the turning load would ordinarily jar, impair and render permanently defective the measuring instrumentalities, but the rod extension 71 is sufficiently flexible to fully absorb this shock.

This is largely if not entirely overcome by the actuator rod extension 71 which is highly flexible, resilient and possessed of only sufficient rigidity to overcome the function of the measuring instrumentalities connected thereto. Consequently, the severe stress and strains resulting from any back-lash action, will be absorbed for the most part by the flexing of the actuator rod extension 71 and thus protect the measuring instrumentalities under such abnormal conditions of abusive operation. The steel spring wire 71 is sufficiently rigid to carry the comparatively small load involved in actuating the indicator instrumentalities without any flex therein and yet sufficiently resilient to absorb any shock created in the abnormal operation of the turning head 32 or shank 25 such as the sudden release of the handle 10 with a full load on the turning member shank 33.

Then, too, the torsional displacement in a torsion-type wrench embodying a comparatively short load turning shank 25, is comparatively small, in that the degree of twist therein would be a minute amount approximating five thousandths of an inch under normal loads. Because the elongated rod 65-70-71 actuates the dial mechanism at its extremity which is the point of maximum displacement, this minute torsional displacement of the load carrying shank 25 is appreciably and accentuated at the dial end of the actuator rod 71. Even though there was an abrupt release of load, therefore, the back-lash in the aforesaid structure would be negligible and the actuator rod 65-70-71 would not be called upon to withstand any appreciable back-lash shock which could, however, be absorbed by the resilient actuator extension 71 which is preferably constructed from small diameter spring steel wire.

With the arrangement of parts above described, it will be apparent that a very simple, inexpensive and highly accurate ratchet torsion measuring wrench has been provided, wherein there are few moving parts and the friction thereof has been reduced to a minimum to preclude variable and inaccurate readings. These features coupled with the fact that the torsional stress created by the turning load is measured at the point of maximum displacement of the elongated dial mechanism actuator rod, eliminates or reduces to a negligible minimum any inaccuracies even at small loads. Whether or not the handle 10 is a part of the casing 11 or the cover plate 17 is immaterial as such constitutes a mere reversal of parts, and the operation is the same irrespective of the arrangement.

While we have illustrated and described a preferred embodiment of this invention, it must be understood that the invention is capable of considerable variation and modification without departing from the spirit of the invention. We,

therefore, do not wish to be limited to the precise details of construction set forth, but desire to avail ourselves of such variations and modifications as come within the scope of the appended claims.

We claim:

1. In a torque measuring wrench, the combination with an elongated rigid handle member, of a work engaging turning head member anchored in one end of said rigid handle member, a casing complementary to said rigid handle member, said work engaging turning head member comprising a turning load resisting shank anchored in said handle member and a work turning element projecting through said casing, a ratchet housing fixed to said load resisting shank in said casing, ratchet means in said housing between said load resisting shank and said work turning element, and an elongated rod anchored 10 to said ratchet housing at a point spaced from its anchorage to said rigid handle member, said elongated rod serving to transmit the degree of their load sustaining movement relative to said handle member, said elongated rod extending 15 along said handle member without being under any load stress or strain in transmitting movement of said head member and calibrated indicating means operatively connected to the free extremity of said elongated rod to measure the 20 degree of twist occasioned in sustaining turning loads imparted by turning a load with said work engaging member.

2. In a torque measuring wrench, the combination with a rigid handle member, of a casing complementary to said rigid handle member, a turning load resisting shank on said work engaging turning head member comprising a cylindrical torsion shank anchored to said handle member, said torsion shank having a substantially enlarged peripheral shoulder spaced from said handle member for confinement in said casing, said turning head member including a work engaging shank journaled in said casing for rotation relative to said torsion shank, a housing fixed to 35 the peripheral shoulder of said load resisting shank, ratchet means in said housing interposed between said torsion and work engaging shanks, an elongated rod anchored to said ratchet housing, a flexible extension on said rod, said elongated rod serving to transmit the degree of their load sustaining movement relative to said handle member, said elongated rod extending along said handle member without being under any load stress or strain in transmitting movement of said 40 handle member and calibrated indicating means operatively connected to the free extremity of said flexible rod extension to measure the degree of twist occasioned in sustaining turning loads imparted by said work engaging shank to said torsion shank relative to said handle member.

3. In a torque measuring wrench, the combination with a handle member including a casing rigid cover plate attached to said casing, a work engaging turning head member comprising a cylindrical torsion shank anchored in said handle member and having a substantially enlarged peripheral shoulder spaced therefrom for confinement in said casing, a housing fixed to the end of said shank, said turning head member including a work engaging shank extension journaled in said torsion shank, ratchet means in said housing interposed between said torsion and work engaging shanks, an elongated rod fixed at one end to said housing and extending along said casing, and indicating means operatively con-

nected to the free extremity of said rod for displacement responsive to torque applied.

4. In a torque measuring wrench, the combination with a handle member including a casing, of a rigid cover plate attached to said handle member casing, a work engaging head member comprising a cylindrical torsion shank anchored in said handle member, said torsion shank having a substantially enlarged peripheral shoulder spaced from said handle member for confinement in said casing, said turning head member including a work engaging shank extension journalled in the casing of said handle member for axial rotation relative to said torsion shank, a housing fixed to the peripheral shoulder of said torsion shank, ratchet means in said housing interposed between said torsion and work engaging shanks, an elongated rod anchored at one extremity thereof to said ratchet housing to transmit the degree of their load sustaining movement relative to said handle member a comparatively flexible extension on said rod, without being under any load stress or strain in transmitting movement of said head member said elongated rod extending along said rigid cover plate for confinement by said casing, and turning load indicating means operatively connected to the free extremity of said flexible rod extension which is displaced responsive to applying force to said rigid cover plate through said handle member.

5. In a torque measuring wrench, the combination with a handle member including a rigid non-yielding plate, of a work engaging turning head member anchored in said handle member proximate to one end thereof, said work engaging head member comprising a uniform shank extending normal to said handle member for connection therewith, an enlarged ratchet housing on the extremity of said shank, said turning head member including a work engaging shank extension coaxially mounted for rotation in said enlarged housing, ratchet means in said housing and interposed between said torsion shank and said coaxial work engaging shank extension, an elongated rod anchored at one extremity thereof to said ratchet housing at a point spaced from the anchorage of its connecting shank to said handle member, to transmit the degree of their load sustaining movement relative to said handle member said elongated rod extending longitudinally of said handle member, without being under any load stress or strain in transmitting movement of said head member said elongated rod terminating in a free extremity proximate to the end of said handle member opposite to said work engaging head member, and turning load indicating means on said handle member for operative connection to the free extremity of said elongated rod which is displaced responsive to applying force to said handle member.

6. In a torque measuring wrench, the combination with a handle member including a rigid non-yielding plate, of a work engaging turning head member anchored in said handle member

proximate to one end thereof, said work engaging head member comprising a uniform shank extending normal to said handle member for connection therewith, an enlarged ratchet housing on the extremity of said shank, said turning head member including a work engaging shank extension coaxially mounted for rotation in said enlarged housing, reversible ratchet means in said housing and interposed between said torsion shank and said coaxial work engaging shank extension, an elongated rod anchored at one extremity thereof to said ratchet housing at a point spaced from the anchorage of its connecting shank to said handle member, to transmit the degree of their load sustaining movement relative to said handle member said elongated rod extending longitudinally of said handle member, without being under any load stress or strain in transmitting movement to said head member said elongated rod terminating in a free highly flexible extremity proximate to the end of said handle member opposite to said work engaging head member, and turning load indicating means on said handle member for operative connection to the free flexible extremity of said elongated rod which is displaced responsive to applying force to said handle member.

7. In a torque measuring wrench, the combination with a handle member including a rigid non-yielding plate, of a work engaging turning head member anchored in said handle member proximate to one end thereof, said work engaging head member comprising a uniform torsion shank extending normal to said handle member for connection therewith and adapted to twist in response to torque, an enlarged ratchet housing fixed to the extremity of said shank, said turning head member including a work engaging shank extension coaxially mounted for rotation in said enlarged housing, ratchet means in said housing and interposed between said torsion shank and said coaxial work engaging shank extension, an elongated rod anchored at one extremity to said ratchet housing to project radially of said torsion shank for rotary movement responsive to any torque twist therein, to transmit the degree of their load sustaining movement relative to said handle member said elongated rod extending longitudinally of said handle member, without being under any load stress or strain in transmitting movement of said head member said elongated rod terminating in a free highly flexible extremity proximate to the end of said handle member, and turning load indicating means on said handle member for operative connection to the free flexible extremity of said elongated rod, which is displaced responsive to applying force to said handle member, said elongated rod and flexible extremity being sufficiently rigid to actuate said turning load indicating means and sufficiently yielding to absorb back-lash occasioned by an abrupt load release on said work engaging turning head member.
